Patented Jan. 18, 1916.

UNITED STATES PATENT OFFICE.

MORRIS SWORZYN, OF WASHINGTON, DISTRICT OF COLUMBIA.

DISPLAY-CABINET.

1,168,760.

Specification of Letters Patent. Patented Jan. 18, 1916.

Application filed October 16, 1913. Serial No. 795,502.

To all whom it may concern:

Be it known that I, MORRIS SWORZYN, a citizen of the United States of America, residing at Washington, in the District of Columbia, have invented certain new and useful Improvements in Display-Cabinets, of which the following is a specification.

This invention relates to the class of inventions known in the art as store furniture.

0 An object of the invention is the provision of a container for merchandise and means whereby several species or samples of certain grades of merchandise of a particular character may be exhibited without necessitating removing the container from the shelf or from having to open the container in order to ascertain the direct nature of its contents.

10 A further object of the invention is the provision of a container of this character wherein merchandise exhibiting means therefor may be adjustably mounted within the container and with such regard to the display opening thereof that will expedite 15 the operation of initially adjusting the sample card behind the opening.

20 A further object of the invention is the provision of a device of this character wherein the exhibiting means may be operatively held against accidental derangement relatively of the display opening when the merchandise containing or exhibiting card is in place.

25 With these and other objects in view, the invention consists of certain novel features of construction, combination and arrangement of parts, as will be hereinafter described and claimed.

30 In the accompanying drawings:—Figure 1 is a perspective view of a portion of the container; Fig. 2 is a vertical longitudinal section therethrough; Fig. 3 is a horizontal section on the line 3—3 of Fig. 2; and Fig. 4 is a perspective view of the exhibiting member.

35 The container is principally designed to be used in connection with suitable exhibiting racks, file cases or the like, and is intended to accommodate varieties of merchandise and to permit merchandise of one variety to be separated from merchandise of another character. The container is in the form of a rectangular receptacle divided into a plurality of compartments A by means of partitions B, it being obviously understood that any suitable num-

ber of such compartments may be employed as may depend upon the number of compartments required and that no particular arrangement of the compartments is necessary 60 so far as the subject-matter of my invention is concerned. It is stated, however, that all of the receptacles are open at their upper ends and are adapted to be closed by a cover C, as shown in Fig. 2 of the drawings. 65

While the container is specifically intended for use by tailors or like merchants for exhibiting their wares, such as buttons, it is apparent that I do not propose to limit myself to this specific use. 70

75 The vertical wall D at one end of the receptacle is provided with a rectangular opening E and at the back of the opening and mounted for movement in the adjacent compartment A is a combined exhibiting and confining member 1. This member is constructed preferably of cardboard and is provided with a main flat body portion 2 having a strip of tape 3 secured thereto and fastened along one of its edges to the bottom of the receptacle so that said member 1 becomes hinged to the bottom in order that it may be moved angularly with relation to the display opening E and adjusted to lie parallel therewith when the sample 80 card is in exhibited condition. Said member 1 is provided at its ends with substantially triangular integral extensions 4 having angular edges 5 which are adapted to rest against the bottom of the adjacent compartment of the receptacle when the member 1 is adjusted to the dotted line position 85 shown in Fig. 2. At this time the edges 5 form stops which engage against the bottom of the receptacle so as to limit the tilting 90 adjustment of the member 1 and permit the same to be held in upwardly diverging relation relatively of said adjacent end D of the receptacle and then combine therewith to form a guide by means of which the exhibiting card may be freely passed into the 95 container and properly lodged at the back of the display opening E. 100

105 The member 1 has one of its extensions 4 provided with a leaf spring or other equivalent yieldable keeper 6 having one end extended through said extension 4 and then upset against one side thereof, as at 7. The spring is then extended against the outer surface of the extension 4, and it is terminally upstruck and curved, as at 8, where it is adapted to engage in a keeper recess 9 110

- formed in the adjacent side of the receptacle or container. The recess 9 is positioned with such regard to the adjacent end D of the container as to cause the member 1 to be held in a direct parallel position with respect to said end D when the exhibiting card is at the back of the displaced opening. The exhibiting card F is of a size whereby it may be readily inserted between the body portion 5 of the member 1 and the adjacent end D of the container and centered relatively of the opening D so that buttons G or different varieties of merchandise or wares may be exhibited through the opening, as shown, to 10 an advantage in Fig. 1. The articles G are equal in number to the compartments A of the container, and it is intended that at least one compartment contain a quantity of a particular button as indicated upon the card. 15 The opening E is so formed that when it is desired to remove the display card F therefrom the hand of the operator may be extended into the opening and pressure of the hand may be then applied to the display 20 card so as to effect a tilting movement of the member 1 and cause the same to be released from its active engagement with the card, as will be understood. The container is provided with a suitable manipulating tab H 25 whereby it may be readily drawn from between other containers when the same are arranged in display racks or the like. The extension 4 of the member 1 which supports the retaining springs is provided with an 30 opening 10 which is adapted to receive the free end of the spring and to accommodate the same in its movement to a released position when the member 1 is moved to a released position. 35 From the foregoing description, taken in connection with the accompanying drawings, the construction and operation of the 40 invention will be readily understood without requiring a more extended explanation. 45 Various changes in the form, proportion and the minor details of construction may be resorted to without departing from the principle or sacrificing any of the advantages of this invention as claimed. 50 I claim:— 1. A receptacle having an apertured wall, a member mounted in the receptacle for swinging movement behind said apertured wall, and said member having inwardly disposed extensions at its ends serving to limit 55 the inward swinging movement of the member. 2. A merchandise container having an apertured front wall, a member pivoted in said container behind said apertured front 60 wall, a card interposed between said member and said front wall, means for limiting inward swinging movement of said member, and means carried by said limiting means to hold said member against said card. 65 3. A merchandise container including an apertured front wall, an inwardly movable member pivoted in said container behind said apertured front wall, angular extensions on said member for limiting inward 70 movement of the latter, said container having concave recesses in its sides, and spring keepers carried by said angular extensions having curved ends adapted to engage in said concave recesses to yieldably hold said 75 member in parallel relation to said apertured front wall.

In testimony whereof I affix my signature in presence of two witnesses.

MORRIS SWORZYN.
